(57) **CLAIM**

The ornamental design for a table, as shown and described.

DESCRIPTION

FIG. 1 is a top perspective view of a table, showing my new design;

FIG. 2 is a left side view of the table, the right side view being identical;

FIG. 3 is a front view, the rear view being identical thereto;

FIG. 4 is a fragmentary perspective view of the inside surface of the rear of the table, the inside surface of the front of the table being identical; and,

FIG. 5 is a fragmentary perspective view of the inside surface of the left side of the table, the inside surface of the right side being identical.

1 Claim, 5 Drawing Sheets
